United States Patent Office.

JOHN JOHNSON, OF SACO, MAINE.

Letters Patent No. 60,898, dated January 1, 1867.

IMPROVED PROCESS FOR OBTAINING THE PRECIOUS METALS FROM THE BEDS OF RIVERS.

The Schedule referred to in these Letters Patent and making part of the same.

TO ALL WHOM IT MAY CONCERN:

Be it known that I, JOHN JOHNSON, of Saco, county of York, State of Maine, have invented a new and improved Process for Obtaining the Precious Metals from the Beds of Rivers; and I do hereby declare that the following is a full and exact description thereof.

The nature of my invention consists in combining with a barge or boat a properly constructed diving-bell, and arranging it as herein set forth, for the purpose of getting down to the bed of the river and of obtaining the gold therein.

To enable others to make and use my invention, I will proceed to describe its construction and operation. I construct a flat-boat, about eighteen feet wide and sixty feet in length, decked over and made water-tight. Near the centre of its width and length, I make a circular aperture of about twelve feet in diameter, so that a bell of suitable diameter and length, when properly suspended, may pass freely through it vertically without touching the sides of the aperture of the barge. The diving-bell I make of suitable sheet iron, and rivet it so that its sides and top shall be air and water-tight. In its construction I use suitable braces and angle iron to render it stiff and firm enough for the use contemplated. In this instance, I make this bell about ten feet diameter and about nine feet high. On the top or crown or deck of this bell or holder, I construct a double-chamber, the inner chamber being directly connected with the bell, and the outer chamber with the inner one by suitable doors or passages. Each of these doors has stop-cocks, and so fixed as to be within the control of an operator. At suitable localities I insert glass, to afford light from without to the interior; and, to obtain all the light practicable, I paint the interior over with several coats of white paint. The bell being constructed and placed within the space in the barge, and properly suspended and balanced, I connect therewith air-supply pipes, and place a suitable air-pump on the barge; so that, at pleasure, a sufficient supply of air may be forced into the bell found requisite for the number of men to be employed therein, this air being rendered of the requisite temperature in its passage from the pump to the bell, by being suitably warmed in a chamber adapted for the purpose. The bell being suspended from on deck, and properly balanced to prevent it being moved from its vertical position, I place stay chains to the bell, and fasten the other ends into suitable eye-bolts near the ends of the barge on the underneath surface, leaving just sufficient slackness of chain that the bell may rest on or be near the bottom of the river without being much from a vertical position, and yet free and clear from the circular opening through the barge, the office of these chains being to hold the bell as near vertical as can be, at the same time keep it in position in a current in the river. Before being lowered for work the barge is safely and securely anchored, that no accident happen to those within the bell. Inside of the bell, and near its lower edge, I have a semicircular shield, with suitable appliances for sliding it up or down. The object of this shield is to serve and aid to deflect the current from coming under the bell, at the same time to deflect it in such a manner as to secure as near still water beneath the bell as is practicable. The purpose of the double chamber is to serve as a means of ingress and egress. When a person wishes to enter the bell, the doors of the double chamber are closed and the stop-cocks set properly; he then steps from the barge upon the deck of the holder or bell, (the air-pump having been previously set going soon puts a tension upon the interior.) He opens the proper valve; this relieves the door of the outer compartment, and it is now opened inward and the party steps in; and, on closing the door after him and making the valve air-tight, he next opens the valve of the inner door. The air escaping from the inner to the outer chamber soon equalizes the tension, thus enabling the inner door to be opened, on opening which the workman steps into the inner chamber, and from thence into the bell, and descends for work. If another follow, he that went forward must leave the conditions in the order he found them, and the like in passing out. Thus, by this arrangement, any person within or without the bell can come or go at pleasure, without inconvenience.

As it is contemplated by the use of this apparatus to obtain the free gold on or near the bed of the river, I further, when found necessary, increase the light for close inspection by adding lamps, portable or otherwise. In some cases I concentrate it by lenses or reflectors, that a closer scrutiny may be had of the bed of the river than if not thus used. When this bell is lowered, and the working party beneath it, with such appliances as are used for obtaining gold from auriferous sands and gravels, and they there use the "tom," or other gold concentrating and saving apparatus in water but a few inches in depth, they will be enabled to effectually wash and

treat gold-bearing sands and gravels. To further aid, I fix on the inside of the bell one or more rotating pumps, so that the required amount of water may readily be obtained. To this pump, hose-pipes with suitable nozzles are attached for the purpose of supplying water for washing and concentrating the sands, and also for the purpose of forcing away the loose sand, that prospecting may be carried on within the bell on or near the bed of the river. It is contemplated that those within the bell control its movements, having within their reach the requisite warping apparatus to enable them to move this bell and flat-boat transversely across the river, the barge or flat-boat having been, previous to operating, anchored and held in the stream or river by anchor and chain of size and length required for the work. Speaking-tubes or other appliances may be employed for communicating to those below or on the barge, as found best in actual practical working. A code of signals, previously agreed upon, may be employed, that the wishes of either party to the other be fully comprehended and acted upon; such as, "To the right or left," "Warp up or let down stream," "Pump in more or less air," "Increase or diminish its temperature," "Elevate or depress the bell," &c., &c. This system by bell and barge will also enable me to explore in advance of employing my dredging system, for which I have applied for Letters Patent.

What I claim, and desire to secure by Letters Patent, is—

The system herein set forth for obtaining gold from the beds of rivers, substantially as specified.

I claim the process by the means employed for the purpose intended, substantially as specified.

JOHN JOHNSON.
